JOHN E. MUHLFELD, OF SCARSDALE, AND VIRGINIUS Z. CARACRISTI, OF BRONXVILLE,
NEW YORK.

SUPPLEMENTAL DRIVE FOR VEHICLES.

Application filed June 24, 1920. Serial No. 391,326.

To all whom it may concern:

Be it known that we, JOHN E. MUHLFELD, a citizen of the United States, and a resident of Scarsdale, county of Westchester, and 5 State of New York, and VIRGINIUS Z. CARACRISTI, a citizen of the United States, and a resident of Bronxville, county of Westchester, and State of New York, have invented certain new and useful Improvements 10 in Supplemental Drives for Vehicles, of which the following is a description.

This invention relates to an improved supplemental drive for vehicles, and primarily has for its object to provide supplementary drive means for a locomotive where- 15 by the adhesive pressure due to the weight of the locomotive upon the rails may be utilized to full advantage in overcoming inertia and accelerating the starting motion of the locomotive.

More particularly our present invention comprehends a supplementary drive of the above character, embodying a gear mechanism for imparting a positive driving impulse to the rear trailer wheels of a locomotive, and a frame in which such drive gearing is operatively mounted, having a three point bearing permitting of the vertical oscillation of such frame relative to the truck 25 frame and the locomotive structure.

It is another object of the invention to provide a supplemental drive means for locomotives, which is applicable to any of the uncoupled wheels of the locomotive, and 30 embodies a construction which is so mounted and arranged that the greater part of the weight of such supplemental drive means is suspended over and borne by the coupled wheels of the locomotive, while a minimum 35 of such additional weight is borne by the uncoupled wheels which are propelled by the supplemental drive means.

Our invention further contemplates the provision of a supplemental drive means for 45 locomotives which is simple and durable in the construction and arrangement of its several parts, and which is directly driven by means of steam generated in the locomotive boiler.

With the above and other objects in view, 50 the invention consists in the improved form, construction and relative arrangement of the several parts, as will be hereinafter more

fully described, illustrated in the accompanying drawings, and subsequently incorporated in the subjoined claims. 55

In the drawings, wherein we have illustrated several preferred and satisfactory embodiments of the invention, and in which similar reference characters designate corresponding parts throughout the several views:

Figure 1 is a side elevation of a locomotive, certain of the parts being omitted to more clearly disclose the application of our 65 present invention thereto.

Figure 2 is a vertical sectional view illustrating the mounting of the supporting frame for the supplemental drive mechanism, and, 70

Figure 3 is a plan view of the supplemental drive unit.

In the accompanying drawings, we have shown a locomotive similar to that disclosed in our prior application for patent, 75 Serial No. 374,721, filed April 17, 1920, but, in so far as the merits of the present invention are concerned, it is to be understood that the supplemental drive mechanism which we shall hereinafter describe in detail, may likewise be applied to other locomotive constructions of the simple, compound, triplex or other type. 80

The locomotive structure generally indicated as 10, is mounted and supported in 85 proper balance upon the main drive trucks 5 and the front and rear trucks 6 and 7 respectively. As is well known, in the customary locomotive construction the wheels of the latter trucks exert no positive tractive 90 effort upon the rails as an aid in the propulsion of the locomotive, but constitute merely guiding and supporting means. However, that portion of the weight of the locomotive which devolves upon the wheels of the 95 rear truck 7 results in a high adhesive pressure of these wheels upon the track rails, and it is the primary purpose of our present invention to provide means whereby such adhesive pressure of these rear trailer 100 wheels 7 may be effectively utilized as a material supplement to the main tractive driving force of the wheels 5 upon the rails, to the end that inertia may be quickly overcome, and the starting movement of the locomotive accelerated. It will, of course, be

manifest that a similar supplemental drive means might also be applied to the leading truck wheels of the locomotive.

As herein shown, the rear truck includes 5 the usual frame in which the wheel supported axle 56 is journaled. In one adaptation of our invention we provide a carrying frame for the supplemental drive gearing, and a flexible three point mounting or bearing therefor, which affords the requisite 10 flexibility and permits of the relative vertical movement of the locomotive body, the truck frame, and the carrying frame without destroying the driving connection. We 15 attain this result by providing the gear carrying frame 55 with spaced bearings loosely surrounding the axle 56. At its rear end and in spaced relation to the axle 56 the frame 55 is swiveled upon the upper end of 20 the post 57, which, in turn, is swiveled at its lower end in a fixed bearing 58. Preferably a spring 59 surrounds the post 57 between the frame 55 and the bearing 58, and serves to yieldingly resist the tendency of 25 the frame 55 to oscillate with respect to the truck frame and the locomotive structure.

Upon the axle 56 spaced cog gears 60 are fixed. Above the axle 56 a shaft 62 is mounted in spaced bearings 62' on the frame 30 55, and pinions 61 are fixed upon said shaft. These pinions have constant meshing engagement with the respective gears 60. A beveled gear 63 is also fixed upon the shaft 62, and meshes with the pinion 64 on the 35 longitudinal shaft 65. This shaft is driven by means of a steam turbine 66, while suitable reducing gearing is interposed in the line of said shaft, as at 67. The shaft 65 consists of a plurality of sections connected 40 by the flexible couplings 65', which permit of the relative axial displacement of the shaft sections. Each shaft section is also connected to the next adjacent section by means of a spline or key indicated at 65", 45 which admits of longitudinal expansion of the engine structure without strain upon the flexible couplings, or disconnection of the shaft sections.

A clutch 68 is also provided for the purpose of interrupting transmission of power 50 to the drive pinion 64. This clutch may be of any desired automatic type, so that when the locomotive has attained a predetermined speed at which the pinion 64 would 55 be rotated through the gearing at a speed in excess of the speed of the driving shaft 65, the clutch will open. In practice the turbine functions until a speed of fifteen to twenty-five miles is attained, when it is 60 thrown out of operation either automatically, or by the manual operation of a suitable cut-off valve in the steam feed pipe 69, which, as herein shown, supplies the turbine with superheated steam from the steam 65 chest pipe connection 40.

It will be understood that the weight of the locomotive structure is so distributed and balanced between the main drivers 5, the front supporting truck 6 and the rear supplementary drive wheels 7 that a considerable adhesive pressure is exerted by the latter wheels upon the rails. Therefore, by the application of a positive driving force to the wheels 7, as above disclosed, a very appreciable additional tractive power 75 is obtained, which materially aids in the propulsion of the locomotive.

It will also be observed that this supplemental drive gearing is directly driven by steam power through the medium of the 80 turbine. However, it is apparent that in place of the turbine, an electrical current generator might be substituted and driven by steam generated in the locomotive boiler, in which case the supplemental drive 85 gearing would be indirectly operated by steam power through the medium of an electrically driven motor. We find, however, that the use of the turbine is more economical, and provides a more positive 90 and reliable power transmission force. In either case it is apparent that the locomotive must be equipped with a boiler of high steam generating capacity, in order to furnish the power necessary for the operation 95 of the supplemental drive gearing, without diminishing the driving power applied for the operation of the main drive wheels 5. It is for this reason that our present invention is preferably to be used 100 in connection with a locomotive of the type and construction disclosed in our prior application, above referred to, or with other locomotive constructions of similar high steam generating capacity.

The supplementary drive means as above described need not necessarily be applied to the leading or trailing wheels of the locomotive, but can be applied for use in conjunction with other uncoupled wheels, 110 which are not driven by the primary drive means of the locomotive. In any case, it is to be noted that the weight of the power generating, driving and transmission mechanisms does not devolve on the truck axle of the uncoupled wheels, so that such weight will not be borne by these wheels. On the contrary, the greater portion of the additional weight will be suspended between and borne 115 by the coupled wheels, which constitute the primary driving means for the locomotive, and function at all times when the locomotive is in operation and using the steam. This is an important feature of our invention since, by relieving the uncoupled wheels 120 of the additional weight of the supplemental power generating, driving and transmission mechanisms, these wheels may be positively driven and caused to function as 125 a supplemental drive means with the con-

sumption of a relatively small proportion of the steam generated in the locomotive boiler. This feature of our improved mounting and arrangement of the supplemental 5 drive means is described and claimed in our copending application hereinbefore referred to.

We have above described a construction, 10 mounting and arrangement of the several parts of the supplemental drive mechanism which we believe will be very reliable and satisfactory in practical operation, but in this respect, likewise, it is to be understood that the present disclosure is susceptible of 15 embodiment in numerous other alternative constructions, and we accordingly reserve the privilege of resorting to various changes or modifications as may be fairly embodied within the spirit and scope of the invention 20 as claimed.

We claim:

1. In combination with a locomotive having primary driving means, a truck sustaining a portion of the weight of the locomotive structure and including an axle and 25 wheels carried thereby, a frame loosely mounted at one of its ends upon said axle so as to partake of its movements at said end, a flexible bearing support for the other 30 end of said frame, drive gearing for said axle mounted in said frame and including a driving shaft, and an actuating motor operatively connected to said shaft and

supported upon the locomotive structure independently of said frame. 35

2. In combination with a locomotive having primary driving means, a truck sustaining a portion of the weight of the locomotive structure and including an axle and 40 wheels carried thereby, a frame oscillatably mounted upon the truck axle, drive gearing for said axle mounted upon the frame and including a driving shaft, a motor supported independently of said frame and driven from the locomotive boiler and a flexible 45 operating connection between said motor and the driving shaft.

3. In combination with a locomotive having main driving wheels and primary driving means therefor, a truck sustaining 50 a portion of the weight of the locomotive structure and including an axle and wheels carried thereby, and driving means for said axle so constructed and arranged that the greater part of the weight of such means 55 is suspended over and borne by the main driving wheels, the driving means for said axle comprising a prime mover and flexible shafting connecting the prime mover with the axle. 60

In testimony that we claim the foregoing as our invention, we have signed our names hereunder.

JOHN E. MUHLFELD.
VIRGINIUS Z. CARACRISTI.
